[57] CLAIM

The ornamental design for a combined AC adapter and battery charger, as shown and described.

DESCRIPTION

FIG. 1 is a front and upper right perspective view of a combined AC adapter and battery charger showing my new design;

FIG. 2 is a front and upper right perspective view of a combined AC adapter and battery charger showing my new design with the sliding cover in the closed position; FIG. 3 is a left side elevational view of a combined AC adapter and battery charger showing my new design with the sliding cover in the open position;

FIG. 4 is a right side elevational view thereof;

FIG. 5 is a top plan view thereof;

FIG. 6 is a bottom plan view thereof;

FIG. 7 is a front elevational view thereof; and,

FIG. 8 is a rear elevational view thereof.
